BAG HOLDING DEVICE

Roy E. Henry, Elba, N. Y.

Application March 22, 1948, Serial No. 16,202

5 Claims. (Cl. 248—101)

1

My invention relates to devices for holding bags on the outlet ends of chutes or the like leading to any vegetable or fruit grading or packing equipment of the type commonly used in packing houses or by individual farmers.

An object of my invention is to provide a device of the character indicated above adapted to open and receive rapidly a standard size bag of cloth or paper.

Another object of my invention is to provide a device of the character indicated above, the grip of which on the bag is automatically strengthened, when the weight of the contents of the bag is being increased.

A further object of my invention is to provide a device of this kind to release the filled bag quickly.

Another object of my invention is to assist the movement of produce as well as to greatly reduce the cost of packing produce in consumer size packages by the saving of time and labor afforded by the use of a device according to my invention.

Other objects of my invention may appear in the following specification describing my invention with reference to the accompanying drawing illustrating a preferred embodiment of my invention. It is however to be understood, that my invention is not to be limited or restricted to the exact construction and combination of parts described in the specification and shown in the drawing, but that such changes and modifications can be made which fall within the scope of the claims appended hereto.

In order that my invention may be better understood, I will now proceed to describe the same with reference to the accompanying drawing, wherein:

Figure 1 is an elevational front view of the device according to my invention;

Figure 2 is an elevational side view of Figure 1 in a somewhat reduced scale;

Figure 3 is a sectional view taken on line 3—3 of Figure 1 in the direction indicated by the arrow head; and

Figure 4 is a sectional view taken on line 4—4 of Figure 1 in the direction indicated by the arrow heads.

The device for holding the bags to be filled embodied herein comprises a substantially cylindrical filling spout 10 provided on its upper end portion with a circumferential flange 11, by means of which the filling spout may be secured to an outlet of a vegetable or fruit grading device or the like (not shown). The lower end portion of the cylindrical filling spout is cut

slantingly to form a pointed lower end 12 adapted to be inserted quickly and easily into the mouth of a paper or cloth bag (not shown). Somewhat above the upper edge portion of the slanting outlet opening of the spout 10 a bracket B is welded on each side of the spout laterally of said upper edge portion. Each bracket B is preferably made from flat steel stock and has a rearwardly extending leg 13 welded to the spout and this leg is bent to project forwardly as shown at 14. Each of these bracket portions extends tangentially to the spout and is secured thereto by welding and is then bent at right angles to extend radially from the spout as shown at 15.

10 An elongated U-shaped hanger H is pivotally suspended on the radial bracket portion 15 by means of a cotter pin 16 extending through holes 17 provided in the upper end portion of the flanges 18 of the U-shaped hanger and through 20 a hole 19 provided in the radial bracket portion 15. On the upper end portion of each hanger flange a grip 20 is formed for a purpose to be described later. The portions of the flanges 18 located just below the grips are curved outwardly to form cams 21 on the lower end of each of which a square shoulder 22 is formed.

25 To each hanger H a gripping plate G is secured as follows: Each gripping plate comprises a body 23 curved to fit against the spout 10. The concave side of each body 23 is lined with rubber, leather or the like, as shown at 24, and centrally on the convex surface of the body a longitudinal rib 25 is provided adapted to fit slidably between the flanges 18 of the hangers H. In each rib a downwardly and inwardly slanting slot 26 is arranged and a pin 27 secured in coaxial holes 28 in the hanger flanges 18 below the cams 21, extends slidably through the slot of the corresponding gripping plate, so that each plate is slidably supported on one of the hangers.

30 In the straight rear portion of each bracket B a hole 29 is provided. A bail-shaped hand lever 30 has straight end portions 31 extending toward each other and located pivotally in the holes 29. To prevent accidental removal of the hand lever from the brackets B a washer 32 is arranged on each straight lever end portion 31 and a cotter pin 33 extends through each lever end portion and secures the washer in place. The hand lever 30 curves about the front of the spout and extends over the upper portions of the hangers H under the grips 20. When the hand lever is 35 swung downwardly it engages the cam portions 21 of the hangers and the gripping plates G are urged into clamping position relative to the spout.

10. On the back of the body 23 of each gripping plate a lug 34 is provided, through which the lower end of a helical spring 35 extends, the upper end of which engages the eye of the cotter pin 16 as shown in Figure 2, so that the gripping plates are normally urged to slide upwardly and outwardly on the pins 27.

When a bag (not shown) is put on the filling spout, the pointed lower end of the spout enters the mouth of the bag quickly and easily. The hand lever is pivoted downwardly, whereby the gripping plates are urged into position to engage the bag and to clamp it against the spout. When the bag is being filled, so that its weight increases and it starts to slip downwardly on the spout, the gripping plates are pulled downwardly too by means of the friction between the bag and the rough friction surface of the pad or lining 24. This downward movement of the gripping plates entails also an inward movement of said plates, strengthening the gripping action of the plates and preventing slippage of the filled bag.

A short upward pivotal movement of the hand lever frees the hangers H and permits the removal of the filled bags. The grips 28 prevent the hand lever from pivoting too far upwardly, so that said lever is always in position to be pivoted downwardly into working position. Simultaneously the gripping plates slide upwardly and outwardly under the action of the helical springs 35.

To facilitate the storing of the above described bag support, a comparatively small plate 36 is welded under the straight rear portion of each bracket B and is provided with a hole 37, so that the bag support can be hung on a hook (not shown) or the like.

I claim:

1. In a bag holder for filling spouts, a pair of hangers pivotally supported at opposite sides of the spout, a bag gripping member supported from each of said hangers, said gripping members being transversely curved to conform to the curvature of the spout, a friction lining on the inner curved face of each gripping member, a pin and slot connection between each hanger and each gripping member, each slot being directed inwardly and downwardly toward the outlet end of the spout to cam the gripping members inwardly to tighten the grip of the same on the bag as the weight of the contents discharged into the bag from the spout increases, and means commonly cooperative with said hangers to force said gripping members into bag holding positions and to release the latter when the bag is ready to be removed from the spout.

2. The invention as defined in claim 1, with a pair of angled brackets horizontally disposed and having their inner legs secured in spaced relation to the rear side of the spout and their outer legs extending tangentially forward at opposite sides thereof and terminating at diametrically opposite points with respect thereto, and flanges out-turned from the forward ends of the said outer legs and having the upper ends of said hangers pivoted to the same.

3. The invention as is defined in claim 1, with the said pins secured in said hangers and the said slots each formed in a vertical substantially triangular rib formed centrally on the outer sides of said gripping members, said slots extending

parallel with the outer longer sides of said ribs, and a coiled spring having one end connected to each of said pins and its other end to each of said gripping members to snap the latter free from contact with the bag for the removal of the latter when filled from the spout upon the actuation of said means to release the gripping members.

4. In a bag holder for filling spouts, a pair of brackets secured at opposite sides of and projecting radially of the spout, a pair of elongate substantially U-shaped hangers each including two spaced side members, each hanger having a bracket disposed between and pivoted to the side members thereof and at one end thereof, a pair of bag gripping members at opposite sides of the spout and each including a rib extending longitudinally of the spout and projecting radially of the spout between the spaced side members of an adjacent hanger, each rib having a slot therein extending obliquely to the length of the rib, a pin extending between the side members of each hanger and through the slot in the adjacent rib, said slots being in downwardly converging relation toward the outlet end of the interposed spout, and means carried by the spout and operatively coupled with the hangers for effecting outward swinging of the hangers on their pivots and movement of the pins in said slots to effect the outward movement of the gripping members away from the spout.

5. In a bag holder for filling spouts, a pair of brackets secured at opposite sides of and projecting radially of the spout, a pair of elongate substantially U-shaped hangers each including two spaced side members, each hanger having a bracket disposed between and pivoted to the side members thereof and at one end thereof, a pair of bag gripping members at opposite sides of the spout and each including a rib extending longitudinally of the spout and projecting radially of the spout between the spaced side members of an adjacent hanger, each rib having a slot therein extending obliquely to the length of the rib, a pin extending between the side members of each hanger and through the slot in the adjacent rib, said slots extending in divergent relation away from the outlet end of the spout, each of said hangers having an outwardly bowed portion between the pivoted end and said pin, the upper end of the bowed portion merging with an outwardly extending grip, and a bail shaped lever pivoted to the spout and enclosing the hangers across said bowed portions for forcing the hangers and gripping members toward the spout when the lever is swung in one direction for engaging the grips and swinging the hangers and gripping members away from the spout when swung in the opposite direction.

R. E. HENRY.
